Claims priority, application Japan Mar. 19, 1969;
Apr. 22, 1969

Term of patent 14 years

Int. Cl. D28—03

U.S. Cl. D95—3

FIG. 10

FIG. 10

FIG. 10

FIG. 10

FIG. 5

FIG. 6

FIG. 7

FIG. 8

FIG. 9

FIG. 10

FIG. 1 is a front elevational view of an electric shaver showing our new design;

FIG. 2 is a rear elevational view;

FIG. 3 is a top plan view;

FIG. 4 is a bottom plan view;

FIG. 5 is a left end elevational view of FIG. 1;

FIG. 6 is a side right end elevational view of FIG. 1;

FIG. 7 is a top plan view of an electric shaver showing another form of our new design;

FIG. 8 is a bottom plan view thereof;

FIG. 9 is a top plan view of an electric shaver showing a third form of our new design; and

FIG. 10 is a bottom plan view thereof.

We claim:

The ornamental design for an electric shaver, substantially as shown and described.
